UNITED STATES PATENT OFFICE.

EDWARD J. PASMORE AND CHARLES Y. McCLURE, OF DENVER, COLORADO.

PIANO-PANEL PROTECTOR.

SPECIFICATION forming part of Letters Patent No. 289,130, dated November 27, 1883.

Application filed April 30, 1883. (No model.)

To all whom it may concern:

Be it known that we, EDWARD J. PASMORE and CHARLES Y. McCLURE, both citizens of the United States, residing at Denver, in the 5 county of Arapahoe and State of Colorado, have invented and produced a new, original, and improved guard for protecting panels on pianos from being scratched or injured by the feet of the performer, of which the following is a specification, reference being had to the accompanying drawings, forming part thereof.

Our invention relates to improvements in piano-front protectors; and the object of our 15 invention is to provide a means of protecting the front parts of pianos from injury by careless persons or children while sitting in front of the same. The protector may be removed and replaced at will, and at the same time presents an ornamental appearance. These 20 objects we attain by means of the device illustrated in the accompanying drawings, forming part of this specification, in which—

Figure 1 is a front view of a piano provided with our improvements; Fig. 2, a sectional end view of Fig. 1 on a line *a a*, showing the extensions *d* and *B* and the rubber attachments *G*.

Similar letters refer to similar parts throughout the several views.

In the drawings, *D* represents the casing in the front part of a piano, *E* the panel thereof, and *C* the base, and *F* a combined pedal-guide and toe-guide. *A* represents our improvement for protecting the front part of the piano, which is made to fit close to either side of and over the upper part of the combined pedal-guide and toe-guide *F*, and extends to near the ends of the front and upward as high 35 as may be desirable. We prefer to have it of a sufficient height to extend above the panel *E*, as shown in Fig. 1 of the accompanying drawings.

The base of the protector *A* is provided with extensions *d d* and *B B*, the latter extending under the base of the piano when the protector is in proper position, and the former extending forward, serving the purpose of a brace and ornament to the protector.

To the back portion of the protector is attached a number of buttons, *G*, by means of screws passing through holes made in the buttons into holes provided in the protector for the purpose of preventing the surface of the protector from coming in contact with the finish on the front of the piano.

The protectors may be manufactured from metallic or wooden materials, as desired. Where pianos are not provided with toe-guides, the protector may be made to fit close to the pedals by making the opening *H* in the lower central part thereof smaller.

The buttons *G* should be made of soft rubber or other pliable material that will not injure the finish on the piano when coming in contact therewith.

Having thus fully described the construction and use of our invention, what we claim as new, and desire to secure by Letters Patent, is—

The hereinbefore-described piano-front protector, consisting, substantially, of the ornamental upright protector *A*, provided at the lower central part thereof with an opening, *H*, and having the extensions *d d* and *B B* permanently attached to the base thereof, as set forth and described, and for the purpose specified.

EDWARD J. PASMORE.
CHARLES Y. McCLURE.
